UNITED STATES PATENT OFFICE.

JAMES E. EVANS, OF ARTESIA, CALIFORNIA, ASSIGNOR OF ONE-HALF TO FRANK W. FOSTER, OF ARTESIA, CALIFORNIA.

CIRCUIT-BREAKER.

1,293,388.

Specification of Letters Patent.

Patented Feb. 4, 1919.

Application filed September 27, 1917. Serial No. 193,483.

To all whom it may concern:

Be it known that I, JAMES E. EVANS, a citizen of the United States, residing at Artesia, in the county of Los Angeles and 5 State of California, have invented new and useful Improvements in Circuit-Breakers, of which the following is a specification.

This invention relates to a circuit breaker and particularly pertains to a device for 10 thermostatically controlling the electric heating circuits in incubators.

The principal object of this invention is to provide an automatically operating thermostat control by which the electric circuit 15 of heating elements may be instantly broken and closed at predetermined temperatures.

Another object of this invention is to provide a device of the above character with simple adjustment whereby the thermostat 20 will positively operate within a given range of temperature.

Other objects will appear hereinafter.

The invention is illustrated, by way of example, in the accompanying drawings in 25 which:

Figure 1 is a view in side elevation illustrating the preferred form of the invention as disassociated from its intended mounting.

Fig. 2 is a view in plan illustrating the 30 form of the device shown in Fig. 1 and further indicating an electric circuit controlled thereby.

Fig. 3 is a fragmentary view in end elevation illustrating the contacts of the device 35 shown in Fig. 1.

Fig. 4 is a fragmentary view in vertical section illustrating the thermostat by which the mechanism is operated.

Fig. 5 is a view in side elevation illustrating a modified form of the invention.

Fig. 6 is a view in plan illustrating the form of the invention shown in Fig. 5.

Referring particularly to Figs. 1-4 inclusive, 10 indicates a base upon which a pair of spaced uprights 11 and 12 are secured. These members are formed with a notch 13 along the rear face of each of the members to provide a seat for tapered shoulders of a spring-balanced lever 14. It 15 will be understood that the notches are horizontally disposed, as well as the lever 14. This lever is substantially rectangular and extends between the standards toward limiting arms 15 and 16 secured at the opposite 20 end of the base. These arms have bent up-

per ends which engage a cross bar at the end of the lever. The opposite end of the lever is shorter and wider so that the weight of the lever upon opposite sides of its pivotal mounting will be substantially counterbalanced. Secured to the forward end of the balanced lever and insulated therefrom is a resilient blade 17 having a V-shaped contact point 18 at its lower end. This point is adapted to be brought to bear 65 against the curved faces of contact members 19 and 20 secured to the base and insulated from each other, where it will properly seat due to its yieldable mounting. An electric conductor 21 is connected with the 70 member 19 and a second conductor 22 is fastened to the member 20.

A central vertical standard 23 is fastened to the base at a point between the position of the contact members and the standards 75 11 and 12. This last-named standard extends upwardly through a large rectangular opening 24 in the balanced lever and provides pivotal support for a tension lever 25. The lever 25 is formed with a downwardly 80 extending end terminating slightly ahead of the pivotal center of the balanced lever and to which a tension spring 26 is secured. The opposite end of this spring is fastened to the rear end of the balanced lever and extends 85 along the center of the rectangular opening therein. The tension lever has a short forked arm 27 at its opposite end between the prongs of which a double collared adjustment nut 28 is disposed. The collars are 90 spaced from each other to permit the apparatus to have considerable movement without strain upon the parts.

The adjustment nut is mounted upon the upper threaded end of a thermostat rod 29 95 which extends downwardly through the base and is secured to the upper plate of an expansive thermostat 30. The thermostat rod extends through a guide tube 31 fixed through the base 10. A trip nut 32 is also 100 mounted upon the threaded end of the rod 29 and has diametrically oppositely extending wings 33 and 34 which normally are positioned laterally of the balancing lever and may be raised to engage the side portions 105 thereof. Normally one wing of the nut is disposed to bear downwardly upon the horizontal leg 35 of a catch bell crank 36, the opposite leg of which extends vertically and is formed with a catch recess 37 110

which may be brought to register with a lug 38 forming a part of the balanced lever, when the pressure of the nut 32 is relieved therefrom.

- 5 The wings 33 and 34 extend from the nut 32 crosswise of the lever 14 and under the ends of the lever so that when the rod 29 is raised by the thermostat the wings will engage the lever 14 and raise the lever and at 10 the same time the bell crank 36 will be raised by the tension of the spring to swing the vertical leg of the bell crank against the lug 38 and when the lever has been raised far enough the lug 38 will pass into 15 the notch 37 and latch the lever 14 in its upper position, and this end of the lever 14 will stay in its upper position until the thermostat contracts and the wing 34 moves downwardly to swing the arm 35 downwardly to bring the lug 38 out of the notch 37, and then the end of the lever will swing 20 downwardly.

In the modified form of the invention shown in Fig. 5, a base 39 is provided upon 25 which a balanced lever 40 is mounted. This lever is mounted between uprights 41 similar to the uprights 11 and 12 in the device previously described. The outer end of the balanced lever is formed with a contact 30 member 42 normally bearing against a similar member 43 secured upon a supporting bracket 44 which extends upwardly in the rectangular opening of the balanced lever. In this case the balanced lever is U-shaped, 35 the open end of the lever being closed by a strip of insulating material 45 to which one end of a tension spring 46 is fastened. The end of this spring is fastened to the downwardly extending end of a tension lever 47 which extends rearwardly and is mounted upon a pivot pin 48 positioned within a bracket 49 upon the base. A thermostat rod 50 passes through an opening in 40 the end of the lever 47 and is there fitted with an adjusting nut 51. The thermostat 45 rod extends downwardly through a guide tube and engages the end of a thermostatic lever 52 which is borne against by a thermostat 53. The lever and thermostat are secured upon a bracket 54 mounted at the lower end of the guide tube.

The two devices described above are provided to control an electric circuit consisting of the two conduits 21 and 22, a source 55 of electric supply 55, and an electric heating element 56. In the one instance, the circuit is completed by forming a contact across the contact members 19 and 20 by the movable member 18, while with the other 60 device the circuit is completed by forming a contact from one upright 41 through the balanced lever 40 thence through the contact members 42 and 43 and to the conduit 22 along the bracket 44.

65 In the operation of the form of the device

shown in Figs. 1-4 it will be assumed that the contact members 19 and 20 are electrically connected due to the fact that the contact 18 is wedged between them. This completes the circuit through the heating element as previously described. When the circuit is thus completed the heating element will be in operation and will be so disposed as to effect the thermostat. As the temperature of the air surrounding the thermostat is raised, the thermostat will expand and the thermostat rod will be moved upwardly, the lower collar of the nut 28 bearing against the forked end of the tension lever to swing the opposite end of the lever 70 downwardly as indicated by the arrow *a*—in Fig. 1. This movement will exert a tension upon the spring 26 and when the lever has passed sufficiently below the center of balance of the balanced lever 14 will act to 75 swing the contact end of the balanced lever upwardly in the direction of the arrow *b*—in Fig. 1. At the time this action takes place, the trip nut 32 will be raised from engagement with the leg of bell crank 36 and will permit its spring 36' to swing it in 80 the direction of the arrow *c*—and cause the lug 38 upon the balanced lever to seat within the notch 37 upon the bell crank. This will positively support the contact 85 member 18 until after the trip nut again strikes the leg of the crank as the thermostat is contracted, after which time the receding movement of the tension lever will 90 act to swing the balanced lever downwardly 95 and reestablish communication between the contacts 19 and 20. Due to this arrangement it is possible to make and break a circuit even though the movement of the initial actuating mechanism is slow. In case 100 the tension spring is broken, the wings upon the trip nut will lift the balanced lever as the thermostat expands, thus making the device proof against accident.

In the modified form of the invention the 110 operation is similar. In this case the expansion of the thermostat is downwardly and acts to swing the thermostat lever 52 in the direction of the arrow *d*—as shown in Fig. 5. This pulls downwardly upon the 115 thermostat rod and causes an upward swinging movement of the tension lever 47 in the direction of the arrow *e*—. This movement is effected against the adjustable counterweight 57 and the tension of the spring 120 46. As the tension lever swings upwardly, the point from which force is applied to the lever will be transferred above the center of balance of the balanced lever and cause it to swing downwardly. When the thermostat contracts the action will be reversed and the contact between members 42 and 43 reestablished.

125 It will thus be seen that the device here disclosed, while simple in its construction, 130

will operate positively and effectively to instantly make and break an electric current when the force controlling the device is slowly acting.

- 5 While I have shown the preferred construction of my circuit breaker as now known to me, it will be understood that various changes in the combination, construction, and arrangement of parts may be 10 made by those skilled in the art without departing from the spirit of my invention as claimed.

I claim:

1. A circuit breaker comprising a slowly 15 expanding thermostat element, a lever actuated by said element, a second lever upon which a contact member is mounted, means whereby a slow movement of the first named lever by the thermostat will cause an instant movement of the second-named lever at a moment during the expansive action of the thermostat, means for adjusting the mechanism to predetermine the moments of instant actuation of the second-named lever, means for instantly restoring the second-named lever to its original position at a given moment during the contraction of the thermostat, means for positively locking the second-named lever in its uppermost 20 position after actuation upon the expansive stroke of the thermostat, and positively acting adjustable means for releasing said second-named lever from the locking means at a point in the contracting 25 stroke of the thermostat.

2. A circuit breaker comprising a base, a thermostatic element mounted beneath said base, a thermostat rod extending upwardly through the base from the element, an adjustable double-collared nut mounted upon the upper threaded end of said rod, a tension lever pivotally mounted above the base and having a bifurcated end, the prongs of which extend along opposite sides of the double-collared nut and between the collars thereof, a tension spring secured at the opposite end of said lever, a balanced lever pivotally mounted upon the base and to one end of which the opposite end of the tension spring is secured, a resilient blade secured to the opposite end of the balanced lever and extending downwardly therefrom, a contact point fastened upon the lower end of said blade, a pair of spaced contact members dielectrically mounted upon the base and between which the point may be engaged, and means whereby a slow movement of the tension lever will at a given moment transfer the tension of the spring to opposite sides of the center of balance of the balanced lever as the thermostat contracts and expands and instantly make and break con-

tact between the contact point and the contact members.

3. A circuit breaker comprising a base, a thermostatic element mounted beneath said base, a thermostat rod extending upwardly through the base from the element, an adjustable double-collared nut mounted upon the upper threaded end of said rod, a tension lever pivotally mounted above the base and having a bifurcated end, the prongs of which extend along opposite sides of the double-collared nut and between the collars thereof, a tension spring secured at the opposite end of said lever, a balanced lever pivotally mounted upon the base and to one end of which the opposite end of the tension spring is secured, a resilient blade secured to the opposite end of the balanced lever and extending downwardly therefrom, a contact point fastened upon the lower end of said blade, a pair of spaced contact members dielectrically mounted upon the base and between which the point may be wedged, means whereby a slow movement of the tension lever will at a given moment transfer the tension of the spring to opposite sides of the center of balance of the balanced lever, as the thermostat contracts and expands and instantly make and break contact between the contact point and the contact members, a trip-nut mounted upon the thermostat rod, a locking member controlled by said trip-nut to temporarily lock the balanced lever in its uppermost position and release it therefrom, and means whereby the trip-nut may actuate the mechanism in the event of the breakage of parts thereof.

4. In a circuit breaker, a balanced lever pivotally mounted in a horizontal plane, a tension lever pivotally mounted above the balanced lever, a spring connecting one end of the tension lever to one end of the balanced lever, said spring being normally substantially parallel with the balanced lever and the end of the spring which is connected to the tension lever being adapted to swing up and down past the plane of the balanced lever, and a thermostat for operating the tension lever.

5. In a circuit breaker, a bifurcated balanced lever pivotally mounted in a substantially horizontal plane, a tension lever pivotally mounted above the balanced lever, with one end swinging through the bifurcation in the balanced lever, a spring connecting the tension lever to the balanced lever, said spring being located in the opening between the bifurcations, and thermostatic means for operating the tension lever.

In testimony whereof I have signed my name to this specification.

JAMES E. EVANS.
